UNITED STATES PATENT OFFICE.

WILLIAM LOVELL PULSON, OF RANDOLPH, MASSACHUSETTS.

APPARATUS FOR OILING STAMPED MATERIALS.

Application filed December 14, 1920, Serial No. 430,734. Renewed June 28, 1923.

To all whom it may concern:

Be it known that I, WILLIAM LOVELL PULSON, a citizen of the United States, residing at Randolph, in the county of Norfolk and State of Massachusetts, have invented new and useful Improvements in Apparatus for Oiling Stamped Materials, of which the following is a specification.

The object of my present invention is the provision of easily manipulated and adjustable apparatus through the medium of which stamped material may be adequately and expeditiously oiled.

To the attainment of the foregoing the invention consists in the improvement as hereinafter described and definitely claimed.

In the accompanying drawings, hereby made a part hereof:

Figure 1 is a front elevation showing my novel apparatus and also showing a strip of metal to be oiled as properly arranged to be passed through the apparatus.

Figure 2 is a side elevation of the apparatus.

Figure 3 is a plan view of the apparatus.

Figure 4 is a vertical section taken in the plane indicated by the line 4—4 of Figure 2, looking in the direction indicated by arrow.

Figures 5, 6, 7 and 8 are detail views illustrative of parts of the apparatus and hereinafter explicitly referred to.

Similar numerals of reference designate corresponding parts in all of the views of the drawings.

Among other elements my novel apparatus comprises a lower oil container 1, preferably cylindrical in form, and an upper casing member 2 of general inverted U-shape. The member 2 includes an upright cylindrical portion 3 arranged in vertical alinement with the container 1, a pendent well portion 4, arranged in parallel relation to the portion 3, and an upper hollow portion 5 through the medium of which the portions 3 and 4 are joined. The portion 5 is provided in its upper side with a filling opening 6, normally closed by a hinged door 7.

Complementary to the container 1 and each of the portions 3 and 4 of the U-shaped member 2 is a bracket 7a. The said bracket 7a respectively comprise portions 8 shaped to receive the respective part to be carried and equipped with a bolt 9 and a wing nut 10, rivets 11 connecting the portions 8 in

opposed relation, and bases 9 adapted to be opposed to and fixed on a wall or other upright support, indicated by 12.

Arranged in and extending upwardly from the container 1 is a wick tube 13, and arranged and depending from the portion 3 of the U-shaped member 2 is a wick tube 14. In each of the said wick tubes is a wick carrier 15 movable rectilinearly, and on each carrier 15 is a lateral arm 16 having a threaded aperture for the engagement of a wick adjusting screw 17 having a knurled head 18, relatively arranged as shown. In each of the wick carriers 15 is arranged a group of wicks 19.

In the practical operation of my novel apparatus the strip of metal 25 to be oiled is placed as shown in Figure 1 and one or both of the groups of wicks are adjusted as occasion demands; it being desirable for at least one-fourth of an inch of each group of wicks to protrude beyond the end of its tube. Adjustment is also made to assure the groups of wicks pressing uniformly upon the strip of metal, and when this provision is made the strip of metal is moved between the groups of wicks whereupon both sides of the strip will be covered with films of oil.

It will be apparent from the foregoing that the well portion 4 of the inverted U-shaped member 2 serves, as its name imports, to hold oil for supplying the wick of the inverted U-shaped member.

Having described my invention, what I claim and desire to secure by Letters Patent, is:

1. Apparatus for oiling metals, comprising a lower oil container, an upper casing of inverted U-shape having a well and an upper connecting portion and a hollow portion pendent from said connecting portion, wick tubes in the container and said pendent portion of the U-shaped casing, wick carriers movable in said tubes, wicks in the wick carriers, the wick complementary to the U-shaped casing having a portion pendent in the well of the casing, and means to adjust each wick carrier independently of the other.

2. Apparatus for oiling metal comprising a lower oil container equipped with a wick tube, a wick carrier adjustable therein, a wick in the tube and means to adjust the wick carrier, an upper U-shaped casing having a well, a pendent portion in parallelism

to the well and an upper portion in which is a filling opening and a door for controlling the same, a wick tube in the said pendent portion of the casing, a wick carrier adjustable in said tube, a wick in the carrier and having a portion pendent in the well, means to adjust the wick carrier, a bracket holding the lower oil container, and separated brackets holding the well and the pendent portion of the inverted U-shaped 10 casing.

In testimony whereof I affix my signature.

WILLIAM LOVELL PULSON.
